UNITED STATES PATENT OFFICE.

GEORGE B. THOMAS, OF HARTFORD, CONNECTICUT, ASSIGNOR TO THE PERKINS ELECTRIC SWITCH MANUFACTURING COMPANY, OF HARTFORD, CONNECTICUT, A CORPORATION OF CONNECTICUT.

ELECTRICAL SNAP-SWITCH.

SPECIFICATION forming part of Letters Patent No. 687,669, dated November 26, 1901.

Application filed September 3, 1901. Serial No. 74,175. (No model.)

To all whom it may concern:

Be it known that I, GEORGE B. THOMAS, a citizen of the United States of America, residing in Hartford, in the county of Hartford, 5 State of Connecticut, have invented Improvements in Electrical Snap-Switches, of which the following is a specification.

My invention relates more particularly to that class of electric snap-switches in which 10 a rotary or oscillating commutator is combined with fixed contacts on the base and means for tensioning a spring to effect a quick partial rotation of the commutator and breaking of the circuit upon release of the catch device by the same movement of the means which tensions the spring.

The main object of my invention is to construct a strong and economically-manufactured commutator of this character and such 20 that while made for single-pole switches it is at the same time adapted for the making up of double-pole or other multiple-pole switches.

In the accompanying drawings, Figure 1 is 25 a perspective view, partly in section, of my improved commutator on an enlarged scale. Fig. 2 is a vertical section, drawn to a smaller scale, of a double-pole switch fitted with a pair of my interchangeable commutator units, 30 the inclosing cover being omitted. Fig. 3 is a sectional plan view on the line 3 3, Fig. 2; and Fig. 4 is a perspective view of a form of spring which may be employed in conjunction with my commutator units.

35 In the drawings I have illustrated my invention as applied to the type of rotary snap-switch which forms the subject of the Gibbs patent, No. 517,100, dated March 27, 1894, and in which there is combined with the stationary contacts of the base a rotary operating-spindle having a screw-thread on which is fitted a nut normally engaging with a lock on the base, but adapted to be released therefrom by the rotation of the spindle, a commutator which turns with the nut, but in 45 which the nut can move lengthwise of the spindle, and a spring connected between the spindle and the nut for rotating the commu-

tator when the nut is released from the lock. The lock and nut constitute a latching device 50 for the commutator.

In the drawings, Figs. 2 and 3, A is the base, of porcelain or other suitable insulating material, and B B' B' are the fixed contacts upon the base.

55 S is the operating-spindle, which at its lower end turns in a bearing in the insulating-base, while at its upper end it carries a thumb-piece t, and it is acted on by a spiral spring D, connected at its upper end to a projection on the 60 spindle and at its lower end engaging in a notch in the nut E. This nut E has ratchet-teeth at its lower end normally held in engagement with ratchet-teeth on the lock F of the base by the end thrust of the spring D. The exterior of the 65 nut E is made of polygonal section, preferably a regular polygon. In the present instance I have shown it as of square section with chamfered corners, Fig. 3. Upon this nut is freely fitted the commutator C. My invention being here shown applied to a double-pole 70 switch, the commutator is in two parts or units C and C' precisely alike and interchangeable, one of the advantages of my invention being that I can build up a commutator with 75 any suitable number of poles with the aid of these independent and interchangeable commutator units. I will now describe the construction of one of these commutator parts as a complete commutator, since one such commutator part is all that is needed for a single-pole switch.

80 As will be seen on reference to Fig. 1, I have shown the contacts on the commutator as consisting of pairs of clips 5 5, the corresponding knife part being on the fixed contacts of the base; but this arrangement may be reversed and the contacts on the commutator may be in the form of single knives to engage spring-clips upon the fixed base. In 85 90 the construction shown the contact-clips 5 5 are formed upon metallic rings 6 6, and the pairs of clips are preferably spaced apart by placing between the rings 6 6 another ring 7. These contact and spacing rings are held together by means of external clamping-rings 95

8 8 and a flanged ferrule 9, with intermediate layers 10 of mica or other suitable insulating material. In order to get the requisite strength in the clamping-rings 8 without unduly increasing the thickness of the finished commutator, I prefer to form these clamping-rings with recesses 11 on their exterior faces at the inner edges of the rings for the reception of the flanges of the securing-ferrule 9.

10 The commutator is thus a self-contained unit shaped internally to be slipped onto and fit easily over the nut E—that is, in the present instance the opening in the ferrule is square, with chamfered corners, as shown in Fig. 1.

15 To make a double-pole switch, two of these commutator units are slipped over the nut E, with the contact-clips of the two commutators set at right angles to each other, as shown in Fig. 3. Between the two commutators I place a spacing-spring—such as a ring G, Fig. 4—with spring-fingers g stamped up out of and bent up from the body of the ring. A cap-plate H, held on the spindle by a retaining-nut h, confines the commutators 20 and spring G in place longitudinally on the spindle, but with sufficient freedom of play to allow the commutators to be self-adjusting when their spring-clips come into contact with the contact-blades B B' on the base 25 upon rotation of the commutator in the usual manner.

I claim as my invention—

1. A commutator unit for electric switches, comprising contact - rings and insulating layers about them with external clamping-rings and a ferrule flanged over the inner edges of the clamping-rings.
2. A commutator unit for electric switches, comprising two contact-rings carrying clip-contacts and insulating layers about them with external clamping-rings and a ferrule flanged over the inner edges of the clamping-rings.
3. A commutator unit for electric switches comprising two contact-rings carrying clip-contacts, an intermediate spacing-ring, and insulating layers about them with external

clamping-rings and a ferrule flanged over the inner edges of the clamping-rings.

4. A commutator unit for electric switches, 50 comprising contact - rings and insulating layers about them with external clamping-rings and a ferrule flanged over the inner edges of the clamping-rings, the opening in the ferrule being polygonal.

5. A commutator for electric switches comprising contact-rings and insulating layers about them with external clamping-rings recessed on their exterior faces and a ferrule flanged over into these recesses at the inner 60 edges of the clamping-rings, substantially as described.

6. An electrical rotary snap-switch, comprising a base with contacts, a rotary operating-spindle having a part of polygonal section, a latching device and spring with a commutator composed of two separate and interchangeable units each having an opening to fit over said polygonal part substantially as described.

7. An electrical rotary snap-switch, comprising a base with contacts, a rotary operating-spindle having a part of polygonal section, a latching device and spring with a commutator composed of two separate and interchangeable parts, each having an opening to fit over said polygonal part, an intermediate spacing-ring and a cap-plate for the commutator units.

8. An electrical rotary snap-switch comprising a base with contacts, a rotary operating-spindle, a latching device and spring with a commutator composed of two separate and interchangeable units, each unit being formed of contact-rings, insulating layers, clamping-rings and a flanged ferrule.

In testimony whereof I have signed my name to this specification in the presence of two subscribing witnesses.

GEORGE B. THOMAS.
